2 SHEETS—SHEET 2.

UNITED STATES PATENT OFFICE.

FREDERICK D. KASTNER, OF SALINA, KANSAS.

AUTOMATIC VALVE-OPERATING MECHANISM.

1,114,145.

Specification of Letters Patent. Patented Oct. 20, 1914.

Application filed August 7, 1913. Serial No. 783,589.

To all whom it may concern:

Be it known that I, FREDERICK D. KASTNER, a citizen of the United States, residing at Salina, in the county of Saline and State of Kansas, have invented certain new and useful Improvements in Automatic Valve-Operating Mechanism; and I do declare the following to be a full, clear, and exact description of the invention, such as will enable others skilled in the art to which it 10 pertains to make and use the same.

This invention relates to improvements in automatic valve operating mechanism.

One object of the invention is to provide 15 an automatic valve operating mechanism designed particularly for use in connection with the water supply for motor pumps whereby the flow of the water to the motor is automatically controlled.

Another object is to provide a device of 20 this character which will be simple, strong, durable and inexpensive in construction, efficient and reliable in operation and well adapted to the purpose for which it is 25 signed.

With these and other objects in view, the invention consists of certain novel features of construction, and the combination and arrangement of parts as will be more fully 30 described and claimed.

In the accompanying drawings: Figure 1 is a top plan view of my improved valve; Fig. 2 is a vertical longitudinal section taken on the line 2—2 of Fig. 1; and showing the parts in position for closing the by-pass valve; Fig. 3 is a similar view showing the parts in position for opening the by-pass valve; Fig. 4 is a vertical cross section taken on the line 4—4 of Fig. 2; Fig. 5 is a 40 similar view taken on the line 5—5 of Fig. 2.

My improved valve operating mechanism comprises a supporting frame 1 which is in the form of a rectangular tray 2 the ends of which extend upwardly at a slight angle and 45 for a considerable distance above the tray as shown. One of the upwardly extending ends of the tray terminates in the form of a combined four-way fitting and valve casing 3 which is disposed parallel with the tray 2 as shown. To the upper branch 4 of the fitting is connected a water supply pipe 5 which leads to and is connected with the city water supply. To the lower branch 6 of the fitting is connected a discharge pipe 55 7 which leads to and is connected with the motor pump (not shown) operated by the

water supply. The outer end branch 8 of the fitting has connected thereto a by-pass pipe 9 which connects with the discharge or waste pipe of the motor. The inner end 60 branch 10 of the fitting is closed by a packing nut 11 through which is adapted to work the stem of a valve hereinafter described.

In the combined fitting and valve casing 3 at the inner end of the by-pass connecting branch 8 is formed a valve seat 12 with which is adapted to be engaged a plug valve 13 which may be of any suitable construction but which is preferably in the form of a tapered body of rubber or other suitable 70 material which is adjustably secured to the inner end of a valve stem 14 by clamping nuts 15 as shown. The valve stem 14 works through the packing nut 11 and has its outer end bent at right angles to form a stud 16 75 for connection with the valve operating mechanism hereinafter described.

Formed on one side of the tray 2 is an upwardly projecting bearing post 17 to the upper end of which is pivotally connected 80 a valve operating lever 18 having a forked or bifurcated lower end 19 and on its upper end an apertured head with which the stud 16 on the valve stem 14 is pivotally engaged, said stud being held in engagement with the 85 apertured head by a washer 20 and cotter pin 21 as shown.

On the upper extremity of the end of the frame opposite to that having the fitting 3 and in direct line with said fitting is formed 90 an offset, circular, skeleton disk or spider 22 which is exteriorly threaded to receive the inner end of a cylindrical valve casing 23 which projects longitudinally from the frame 1 and has its outer end closed and 95 provided with an apertured nipple 24 to which is connected a pipe 25 which leads to and is connected with the soft water discharge pipe of the motor (not shown). A fluid-tight connection is formed between the 100 nipple 24 and the pipe 25 by means of a stuffing box 26 with which the nipple is provided. The inner end of the nipple communicates with the adjacent end of the spring casing 23 through angularly disposed fluid inlet ports 27 through which the fluid in the tank is permitted to enter this end of the valve casing for a purpose hereinafter described.

Slidably mounted in the valve casing or 110 cylinder 23 is a piston 28 having a cup-washer packing 29 secured to the piston 28

by a clamping plate 30 and clamping nut 31 which are screwed onto the end of a piston rod 32 which is preferably square for a distance corresponding substantially to the length of the spring casing or cylinder 23, said squared portion of the piston rod working through a square aperture in the disk or spider 22, arranged in the spring casing or cylinder 23 and coiled around the piston rod 32 between the piston 28 and the spider 22 is a coiled piston retracting spring 33. The outer end of the piston rod may be round and is bent to form an elongated or substantially rectangular loop 32a which is disposed above one side of the frame 1 as shown.

Formed on the side of the tray 2 of the frame directly opposite to the post 17 is a bearing lug 34 on which is pivotally mounted an upwardly projecting lever operating arm 35 on the upper end of which is arranged a weight 36 the purpose of which will be hereinafter described. On the pivoted end of the arm 35 is a laterally projecting stop lug 37 which, when the lever operating arm 35 is swung over to the left or to a position for causing the valve operating lever 18 to open the valve 13, will engage the bottom of the tray 2 and thus limit the movement of the arm 35 in this direction. Arranged on and preferably formed integral with the arm 35 a suitable distance above the pivoted lower end thereof and in position to engage the forked lower end 19 of the lever 18 is a laterally projecting tapered stud 38 the outer end of which projects between the formed end 19 of the lever and is adapted to be brought into engagement with one or the other of the fingers thereof when the arm 35 is swung in one direction or the other. In the bottom of the tray portion 2 of the frame 1 is formed a centrally disposed drain opening 39 through which any water leaking through the packing nut 11, may pass.

As hereinbefore stated my improved valve operating mechanism is designed particularly for use in connection with the water supply for operating motor pumps and especially for motor pumps for forcing or pumping soft water from cisterns into a closed tank under air compression and located in the basement or other part of the building. In other forms of motor pumps employed for this purpose there is a great deal of water wasted in the operation of the motor and it is the principal object of the present invention to overcome or decrease in a great measure the loss or waste of this water. With this end in view, it will be seen, that by means of the construction herein shown and described, when the water in the tank has reached a predetermined pressure or a pressure sufficient to overcome the resistance of the spring 33 in the casing 23,

the pressure of this water which enters the spring casing 23 through the pipe 25 will force the piston back into the cylinder, thus projecting the piston rod 32 a sufficient distance to swing the lever operating arm 35 over toward the opposite side of the frame 1 and past the center of gravity of this lever whereupon the weight 36 on the upper end of the arm will swing the latter to the full limit of its movement as is clearly shown in Figs. 2 and 3 of the drawings. The arm 35 when thus swung over by its weight 36 will bring the stud 38 thereof into forcible engagement with the opposite finger of the forked lower end of the lever 18, thus swinging the upper end of said lever in a reverse direction. This movement of the lever 18 will retract the valve 13 thus opening the by-pass of the valve casing or fitting 3. When the by-pass is thus opened the pressure of the water will be removed from the motor as the greater part of the water will pass from the water supply pipe 5 directly into the by-pass pipe 9 and by this pipe will be carried around the motor. As soon as the pressure in the tank has lowered to a sufficient extent to permit the spring 33 to again expand, the piston 28 in the valve casing will be moved outwardly, thus swinging the valve operating arm 35 in the reverse direction. The reverse movement of the arm 35 will bring the stud 38 thereon into engagement with the opposite finger of the valve operating lever, thus rocking the latter in the proper direction for closing the by-pass valve and again permitting the water supply to pass directly to the motor. By this arrangement it will be seen that the flow of the water to the motor is automatically controlled by the pressure or amount of water pumped into the tank by the motor pump in connection with which this device is employed.

From the foregoing description taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of the invention as claimed.

Having thus described my invention, what I claim is:

1. In a device of the class described, a supporting frame, longitudinally spaced valve and piston casings mounted on said frame in the same horizontal plane, a valve seat at the outer end of said valve casing, a valve for engagement with said seat, a lever fulcrumed intermediately of its ends on said frame, a valve stem attached to said valve and engaged with the upper end of said lever, a piston rod extending through

the casing thereof with its free end bent to form a loop, an arm pivoted to one end of said frame and having a weight on its free end and means on its other end for limiting 5 the swinging movement of said arm in one direction, said arm extending through said piston rod loop and limited in its opposite movement thereby, means on said arm for engaging the free end of said lever and a 10 pressure controlled piston fixed on said piston rod for operating said rod and actuating said arm to shift said lever in opposite directions.

2. In a device of the class described, a 15 frame having a combined four-way fitting and valve casing thereon, a water supply pipe and by-pass pipe connected with said valve casing and fitting, a pipe to connect the fitting with a motor pump, a valve in 20 said valve casing designed to open and close said by-pass pipe, a stem connected with said valve, a valve operating lever pivoted in said frame and connected at one end with said valve stem, said lever having its 25 other end forked, a valve operating arm piv-

otally mounted in said frame and having an over-balancing weight, a stop on said arm for engagement with said frame to limit the movement of the arm in one direction, a stud carried by said arm and adapted to 30 engage the forked end of said valve operating lever, whereby the latter is actuated by said arm to open and close said valve when said arm is swung in one direction or the other, a spring casing arranged on said 35 frame, a piston slidably mounted in said casing and adapted to be moved in one direction by fluid pressure, a spring to move said piston in the opposite direction, and a piston rod connected with the piston and 40 having a loose connection with said lever operating arm.

In testimony whereof I have hereunto set my hand in presence of two subscribing witnesses.

FREDERICK D. KASTNER.
